ARTICLE ISOLATING AND SHOCK ABSORBING SHIPPING CONTAINER

Howard G. Beck, Wabash, Ind., assignor to The General Tire and Rubber Company, Akron, Ohio, a corporation of Ohio

Application June 29, 1950, Serial No. 171,221

7 Claims. (Cl. 206—46)

1

This invention relates to shipping containers for articles such as scientific instruments and expensive machines or machine parts and is so constructed as to absorb impact shocks and protect such instruments or machinery from damage due to accidental impacts to which the containers may be subjected during shipment.

The shipping container of the present invention comprises an inner article carrying frame that is movably mounted within an outer frame and isolated from the outer frame by supporting and cushioning devices designed to offer yielding resistance to movement of the inner frame in any direction in a given plane.

The cushioning and supporting devices are also designed to offer a resistance which first increases rapidly upon initial movement of the inner frame within the outer and then less rapidly in order to more effectively absorb severe impact shocks.

The invention has for its object to provide a shipping container that will afford effective protection to expensive instruments and machinery during shipment.

The invention also has for an object to provide simple and compact cushioning means which will effectively absorb impact shocks with a minimum movement of the article holder in the container.

Reference should be had to the accompanying drawings forming a part of this specification, in which:

Figure 1 is a plan view of a shipping container embodying the invention;

Fig. 2 is a side elevation of the container;

Fig. 3 is a fragmentary horizontal section on an enlarged scale taken on the line indicated at 3—3 in Fig. 2;

Fig. 4 is an end elevation of the container with portions broken away and shown in vertical section;

Fig. 5 is a fragmentary horizontal section on an enlarged scale, taken on the line indicated at 5—5 in Fig. 2;

Fig. 6 is the same section as Fig. 5, showing the inner frame shifted with respect to the outer frame;

Fig. 7 is a sectional view similar to Fig. 5, showing a modified form of seat for the rubber cushioning balls;

Fig. 8 is a horizontal section similar to Fig. 5, showing the cushioning device employing steel balls and spring pressed seats; and

Fig. 9 is a sectional view corresponding to Fig. 8 showing the inner frame shifted with respect to the outer.

2

The container of the present invention has a rigid outer frame provided with longitudinally spaced bottom cross bars 1 of angle form which have vertically disposed flanges 2 which are adapted to engage a floor and space the bottom of the container above the floor to facilitate the entry of lifting forks beneath the container or the passing of a hoisting chain or cable under the container.

10 Longitudinal channel plates 3 are attached to opposite ends of the spaced bottom cross bars 1, and the bottom structure is braced by means of gusset plates 4 which are interposed between the channel plates 3 and the bars 1 and which extend inwardly past the inner sides of the channel plates 3. The channel plates 3 face upwardly, having upwardly extending inner and outer flanges 5. The flanges 5 serve to position upright side walls 6 of the container and upright inner wall sections 7 which are spaced inwardly from and parallel to the upright walls 6 and which are spaced longitudinally to provide openings 8 between the sections at longitudinally spaced points. The parallel upright walls 6 and 15 7 are connected at the top by downwardly facing channel plates 9 which may be identical with the channel plates 3, and the walls 6 and 7 at the ends of the container are connected by end channel plates 10.

The side walls 6 and inner wall sections 7 connected by the channel plates 3, 9 and 10, provide a rigid longitudinal side wall structure for the container at each side thereof, and within the wall sections 7 there is mounted an inner article carrying frame which has longitudinally spaced cross members 11 which are in the form of supporting cradles having their top edges curved to provide article receiving seats 12. The cross members 11 have end members 13 attached thereto which are preferably in the form of castings to provide rigid supports to which the article to be shipped may be bolted or clamped.

45 The cross members 11 of the inner frame are connected by tie rods 14 which have shoulder portions 15 that engage the inner sides of the cross members 11. The tie rods extend through the cross members 11 and are clamped thereto by means of nuts 16. Each of the end members 13 carries a horizontally disposed outwardly projecting trunnion 17 that is provided with a ball-shaped outer end 18. Each trunnion 17 has a tapered shank 19 that fits in a tapered hole in an end member 13 and is held in place by a nut 20. The cross members 11 are positioned in alignment with the openings 8 between the wall sections 7 and the end members 13 project into

these openings. The ball end 18 of each of the trunnions is engaged by socket plates 21 and 22 that are clamped upon the ball 18 and that receive between them an upright plate 23 that extends throughout the major portion of the length of the container substantially midway between the walls 6 and 7. The plates 21 and 22 are vertically elongated and have centrally disposed socket portions 24 and 25 that are clamped upon the ball portion 18 of the trunnions. The plates 21 and 22 are clamped together on the trunnions and to the elongated plate 23 by means of bolts 26.

Above and below each of the trunnions 17 are horizontally disposed cylindrical barrels 27 mounted in the plates 21 and 22. The plates 21, 22 and 23 have registering openings to receive the barrels 27 which are positioned by flanges integral therewith which engage with the outer faces of the plates 21. The barrels 27 are open at their outer ends and have closed inner ends 29, and slidably mounted within each barrel is a follower 30 provided at its outer end with a semi-spherical recess 31 to receive a steel bearing ball 32. Each follower 30 is pressed outwardly by a spring 33 interposed between the follower and the bottom 29 of the barrel, and the balls 32 bear against a steel plate 34 attached to the inner face of the wall 6. Four bearing plates 34 are provided, one opposite each of the openings 8 and each bearing plate 34 is engaged by two vertically spaced bearing balls 32. Each of the plates 34 has vertically spaced concavities 35 in which the balls 32 are normally engaged to hold the inner frame in a substantially fixed position with respect to the outer frame.

The elongated upright plates 23 have two longitudinal rows of disks 36 attached to each face thereof. The disks 36 are disposed back to back facing the wall sections 7 and the side walls 6, and the wall 6 has rows of disks 37 attached to its inner face, the disks 37 being of substantially the same size as the disks 36, and a disk 37 being positioned opposite each of the disks 36. The outer faces of the wall sections 7 have disks 38 which are disposed opposite the disks 36 on the plate 23. The disks 36, 37 and 38 provide seats 39 which are disposed in opposed pairs on opposite sides of the plate 23. The seats 39 are preferably concave and at least one set of each opposed pair has a central depression 40 which provides a circular shoulder 41 which is disposed at a deeper inclination than the surrounding portion of the seat. An elastic rubber ball 42 is interposed between each pair of opposed seats, and these balls normally seat in the depressions 40 as shown in Fig. 5 of the drawings.

The elastic rubber balls 42 have rolling engagement with the opposed seats 39 and serve to yieldingly resist movements of the plates 23 in any direction in the plane of the plates and, since the plates 23 support the inner article carrying frame, the article carrying frame is permitted to have movements in any direction parallel to the side walls of the container and these movements are cushioned by all of the balls 42, each of which offers resistance to movement of the inner frame in any direction parallel to the side walls. The engagement of the balls 42 with the relatively steep shoulder portions 41 of the seats causes the balls to offer a resistance to movements of the inner frame which increases quite rapidly during the initial portion of the movement and less rapidly after the initial movement. The resistance to lateral movement increases throughout

the movement of the inner frame until the movement of the inner frame is stopped, but the initial high rate of increase of resistance, followed by a lesser rate of increase, serves to effectively absorb severe impact shocks.

As herein shown, the cushioning balls are arranged in pairs on opposite sides of each of the plates 23. It is to be understood, however, that each of the cushioning balls functions in exactly the same way as every other ball, and as many of the cushioning balls may be provided as is desirable for the particular article that is to be shipped. In some instances it may be desirable to employ balls only on one side of each of the plates 23. Furthermore, it will be apparent that substantially the same cushioning characteristics can be obtained by confining a cushioning ball between a flat plate and a concave seat such as herein shown.

20 The bearing balls 32 and plates 34 serve to guide the movements of the inner frame within the outer frame and when the balls 32 are engaged in the recesses 35, the balls 32 and plates 34 serve as releasable supporting members to 25 normally hold the inner frame in a fixed position with respect to the outer frame, supporting all or a considerable portion of the weight of the inner frame so that the cushioning balls 42 are subjected to a minimum pressure except when 30 the inner frame is jarred loose from its anchorage by a severe impact. The recesses 35 have a radius of curvature slightly greater than that of the balls 32 so that they allow a slight play of 35 the inner frame within the outer to absorb vibrations, but normally hold the inner frame against substantial movement with respect to the outer frame. When the container is subjected to a severe impact the balls 32 are moved out of the recesses 35 onto the flat portions of 40 the plate, after which the inner frame continues to move until its movement is checked by the elastic balls 42. The distortion of the balls 42 due to movements of the inner frame within the outer causes them to exert a thrust on the 45 plate 23 and through the plate 23 to the inner frame, tending to restore the inner frame to its original position where the bearing balls 32 engage in the recesses 35.

50 In Fig. 7 of the drawings a modified form of seat is shown which may be applied to the structure heretofore described. In this modification concave seats 43 are provided and these seats have central depressions 44 of somewhat greater diameter than the depressions 40 previously described, and these depressions form circular shoulders 45 which have a retarding action on the balls shortly after initial movement of the inner frame, the balls 42 being normally supported in the central portion of the concave depression 44 and out of engagement with the shoulders 45.

55 In Figs. 8 and 9 of the drawings a modified form of cushioning device is shown which may replace the cushioning device shown in Figs. 1 to 6. In this modification the inner frame is provided with trunnions 53 which support the longitudinal upright plates 51 adjacent to and parallel with the upright side walls of the container. The plate 51 has rows of disks 52 that 60 are provided with concave oppositely facing seats 53 each provided with a central depression 54 providing shoulders 55 which have a steeper inclination than the surrounding portions of the seat.

65 Steel bearing balls 56 have rolling engagement

with the seats 53 and are normally seated in the depressions 54 as shown in Fig. 8. Movement of the plate 51 in any direction in its own plane causes the seats 53 to have a wedging action on the balls 56, tending to move them laterally away from the plates 51, and to permit this movement and to provide cushioning action a yielding seat is provided between each of the balls and the fixed wall toward which it moves.

As herein shown, the balls 56 engage with seats 58 identical with the seats 53 and attached to floating plates 59 and 60 that are disposed between the plates 57 and the side walls 6 and wall sections 7 of the container. Springs 61 interposed between the plates 59 and 60 and the walls 6 and 7 press the plates 59 and 60 toward the plates 51 and normally hold the balls in the position shown in Fig. 8. Upon an excessive impact the inner frame moves within the outer, causing the seats 53 to be shifted with respect to the seats 58 and causing the balls to roll from the depressions 54 of the seats 53 over the shoulders 55 to a position such as shown in Fig. 9. The shoulders 55 serve to provide a high initial resistance to movement and the outer portions of the seats 53 serve to provide a more gradual increase in resistance after the balls have passed over the shoulders 55.

The pressure of the springs 61 tends to return the seats 53 and the inner article holding frame to its original position in substantially the same way that the frame is returned by the elastic rubber balls 42.

It is to be understood that in accordance with the provisions of the patent statutes, variations and modifications of the specific devices herein shown and described may be made without departing from the spirit of the invention.

What I claim is:

1. An article isolating shipping container comprising an outer frame and an inner article carrying frame, a pair of oppositely facing concave seats attached, one to each of said frames, said seats being disposed in substantially parallel relation and one having a central depression, the marginal portion of which is at a steeper radial inclination than the portions of the seat surrounding the depression, and means for yieldably supporting the inner frame within the outer comprising an elastic rubber ball held under pressure between said seats and in rolling engagement therewith, said ball normally engaging in said depression whereby the steep marginal portions of said depression provide a relatively high initial resistance to movements of the inner frame with respect to the outer.

2. An article isolating shipping container comprising an outer frame, an inner frame, outwardly facing concave seats carried by the inner frame at opposite sides thereof, inwardly facing concave seats carried by the outer frame and arranged, one facing each of the inner frame seats, a rubber ball held under pressure between each two opposed seats and in rolling engagement therewith, and releasable means for normally supporting the weight of the inner frame independently of said balls comprising a flat upright plate carried by one of said frames and provided with a concave socket, a hard rounded bearing member carried by the other frame, and means for yieldingly holding said bearing member in said socket.

3. An article isolating and cushioning shipping container comprising an outer frame having upright side members, longitudinally spaced in-

wardly facing concave seats carried by said members, an inner frame, outwardly facing concave seats carried by said inner frame, one opposite each of the seats of the outer frame, each of said seats having a central circular depression the marginal portion of which is radially inclined and a portion surrounding the depression which has a radial inclination less steep than the marginal portion of the depression, and an elastic rubber ball under pressure between each two opposed seats and in rolling engagement therewith, said balls normally seating in said depressions whereby the steep marginal portions of the depressions provide high initial resistance to relative movements of said frames.

4. An article isolating and cushioning shipping container comprising an outer frame having upright side members, longitudinally spaced inwardly facing concave seats carried by said members, an inner frame, outwardly facing concave seats carried by said inner frame, one opposite each of the seats of the outer frame, parallel upright plates carried by the outer frame, bearing members carried by the inner frame and engaging said plates to constrain the inner frame to movements in directions parallel to said plates, and elastic rubber cushioning balls interposed between said seats for cushioning relative movements of said frames.

5. An article isolating and cushioning shipping container comprising an outer rigid frame having upright side walls, longitudinally spaced bearing plates attached to the inner face of said wall, each of said plates having a flat inner bearing face provided with a concave socket, an inner rigid article carrying frame having rounded bearing members mounted for lateral movement therein and adapted to slide on said plates and engage in said sockets, springs pressing said bearing members toward said plates to normally hold the same in said sockets so that the weight of the inner frame is normally carried by said bearing members, longitudinally spaced concave seats carried by said walls, opposed concave seats carried by the inner frame, and elastic rubber balls confined between said seats in rolling engagement therewith to yieldably resist movements of the inner frame in the outer in any direction parallel to said side walls.

6. An article isolating and cushioning shipping container comprising an outer rigid frame having upright side walls, longitudinally spaced bearing plates attached to the inner face of said wall, each of said plates having a flat inner bearing face provided with a concave socket, an inner rigid article carrying frame having rounded bearing members mounted for lateral movement therein and adapted to slide on said plates and engage in said sockets, springs pressing said bearing members toward said plates to normally hold the same in said sockets so that the weight of the inner frame is normally carried by said bearing members, longitudinally spaced concave seats carried by said walls, opposed concave seats carried by the inner frame, and elastic rubber balls confined between said seats in rolling engagement therewith to yieldably resist movements of the inner frame in the outer in any direction parallel to said side walls, each of said seats having a central depression to receive the ball confined by it, the said depression having a marginal wall that is more steeply inclined along radial lines than other portions of the seat whereby said balls offer a relatively high resistance to

initial movements of the inner frame in the outer.

7. An article isolating and cushioning shipping container comprising a rigid outer frame having elongated upright and parallel side walls and uprights spaced inwardly from each of said side walls, longitudinal rows of concave inwardly facing seats attached to the inner faces of said side walls, concave outwardly facing seats carried by said uprights, one opposite each of the seats of the side wall, an inner article carrying frame within the outer frame, said inner frame having elongated upright plates attached thereto and disposed between said side walls and said uprights, said plates having inwardly and outwardly facing concave seats arranged back to back in rows and facing the seats of the side walls and uprights, and elastic rubber balls confined between the seats of the plate and the opposed seats of said side walls and uprights, each ball having

rolling engagement with the seats between which it is confined and yieldingly resisting movements of the inner frame in the outer in any direction parallel to said side walls.

HOWARD G. BECK.
